(Cl. D48—23)

FIG. 1

FIG. 2

FIG. 3

FIGURE 1 is an elevational view of a lighting fixture showing my new design.

FIGURE 2 is a top view thereof.

FIGURE 3 is a bottom view thereof.

The side opposite that shown in FIG. 1 is a mirror image thereof.

The cord shown in broken lines in FIGS. 1 and 3 is for illustrative purposes only. The dominant features of my design reside in the full line showing.

I claim:

The ornamental design for a lighting fixture, as shown and described.
